UNITED STATES PATENT OFFICE.

WILLIAM W. SABIN, OF PORTLAND, OREGON.

DEMOUNTABLE LAMP-BRACKET FOR AUTOMOBILES.

1,340,686.

Specification of Letters Patent. Patented May 18, 1920.

Application filed May 2, 1919. Serial No. 294,325.

To all whom it may concern:

Be it known that I, WILLIAM W. SABIN, a citizen of the United States, and a resident of the city of Portland, county of Multnomah, State of Oregon, have invented a certain new and useful Improvement in Demountable Lamp-Brackets for Automobiles, of which the following is a specification.

The object of my invention is to provide a lamp-bracket of inexpensive construction adapted for being demountably secured on the upright post of the windshield of an automobile. Also to provide means for locking the bracket, and the lamp globe or light carried thereby, in place, so that it can not be removed by any other person than the one possessing the key to the lock.

A further object is to so arrange the lamp bracket that the light carrying part may be readily demounted and carried about as a trouble lamp.

I attain my objects in the device illustrated in the accompanying drawings, in which:

25 Figure 1 is a side elevation of my device;

Fig. 2 is a longitudinal, vertical section with respect to Figs. 1 and 3, being taken on the line 2-2 of Fig. 3, with the lamp holding arm arranged, however, in longitudinal alignment with the body of the bracket, and the mirror carried by the lamp member disposed at right angles to the latter; these arbitrary arrangements of said arm and bracket being adopted merely as a matter of convenience in illustrating in assemblage all the parts embodied in my lamp bracket;

Fig. 3 is a longitudinal section on the line 3-3 of Fig. 1;

40 Fig. 4 is a vertical cross section on the line 4-4 of Fig. 1, looking in the direction pointed by the arrow;

Fig. 5 is a sectional detail of the spool on which the cord is wound; and

45 Fig. 6 is a detail of the means for clamping the lamp post against rotation.

The body or case of my bracket is of rectangular form, except at the bottom, and comprises two half parts *a*, *b*, hinged together at *c*, and provided with companion half neck portions *d*, adapted for being clamped on the post of the windshield frame. Nuts and bolts *e* secure the two bracket parts together. The two bracket parts are further locked together by a lock mechanism

which is understood to be contained in the barrel *f*, and including a spindle *f'* provided with an arm *f''*, which spindle may be rotated by means of a key inserted through the lock shield *g*, so as to cause the arm *f''* to assume one of the two positions shown in full lines and dotted lines in Fig. 2.

The arm *f''* of the spindle *f'* engages with a longitudinally slideable bolt *h*, provided with a slot *i*, in which said arm bears. The bolt *h* has a concaved end *j* adapted for engaging with the peripheral groove *k* of the lamp-supporting post *k'* having a curved upper end. The lock mechanism is so constructed that in the partial rotation of the spindle *f'* to the right it will first move the bolt *h* sufficiently to disengage the lamp post *k'*; and in the further rotation of the spindle *f'* to the right, the arm *f''* of the latter will be withdrawn from the bolt *h* completely, so that upon the removal of the bolts *e* the two wall sections, *a*, *b*, of the case may be opened on their hinge. Thus it is evident that neither the lamp post can be removed nor the bracket detached from the post of the windshield frame by any person not possessing the key for the lock. The lamp post *k'* is rotatably mounted in the part, *a*, of the case, and on its upper end is swiveled, as at *l*, a lamp carrying arm *l'*, supporting at one end a reflector *m*, in which is inserted an electric light globe *n*.

In the opposite end of the arm *l'* is threaded a piece *o*, having a hinge *o'*, to which is hinged at *p'* an arm *p*, carrying a mirror *q*; the hinges *o'* and *p'* co-operating to form a universal joint.

In order to rigidly hold the lamp arm *l'* in the position to which it is adjusted, I provide a concaved clamping head *r*, mounted on a pin *r'* projecting from the piece *o*, and bearing on a spring *s*, so that by screwing up the piece *o* tightly the parts will be jammed together.

In the lower part of the frame is rotatably mounted a spool *t*. On the spool *t* is wound an electric light cord. One hub of the spool is assumed to be connected, as at *u*, with the poles of an electric battery, not shown, and the electric cord end *v* is also connected to these poles. The free end of the cable *v* is electrically connected with the lamp socket *w* in the usual manner; and the lamp socket is of the usual construction. The spool is controlled by a coil spring *x*; the arrange-

ment being such that when the cord *v* is pulled off the spool *t*, as in the case of removing the lamp post *k'* and using the lamp for illuminating some part of the automobile, 5 then the coil spring *x* is placed in tension, and as the pull on the cord is released the coil spring will act to wind it up again on the spool.

The lamp post is secured against rotation 10 by a jam screw *y* threaded into the case side *b* and detailed in Fig. 6. The jam screw *y* is provided with a reduced end *y'* on which is rotatably mounted a concaved clamping head *z*; and a spring *2* is mounted on the 15 reduced end *y'* so as to obtain a constant bearing of the head *z* on the periphery of the lamp post. The jam screw *y* is made with a handle *3*. Fig. 6 serves also to illustrate the details of construction of the 20 clamping head *r* and related spring *s*, shown in Fig. 2.

The wire cord *v* leads from the spool *t* through a hole 4 in the top of the bracket part, *a*, and through a hole 5 in the lamp 25 carrying arm *l'*, said lamp carrying arm being hollow.

I claim:

1. A lamp bracket comprising two parts hinged together, each part provided with 30 half of a clamping neck for affixing to a support, a lamp post removably and rotatably mounted in one bracket part, means for locking the bracket parts together, means operated by said locking means preventing the removal of the lamp post while the bracket parts are locked together, and means for holding the lamp post against rotation.

2. A lamp bracket comprising two parts 40 hinged together, each part provided with half of a clamping neck for affixing to a support, a lamp post removably and rotatably mounted in one bracket part, means for locking the bracket parts together, 45 means operated by said locking means preventing the removal of the lamp post while the bracket parts are locked together, means for holding the lamp post against rotation, a lamp carrying arm swiveled on the lamp

post, and means for holding said arm 50 against rotation.

3. A lamp bracket comprising two parts hinged together, each part provided with half of a clamping neck for affixing to a support, a lamp post removably and rotatably mounted in one bracket part, means 55 for locking the bracket parts together, means operated by said locking means preventing the removal of the lamp post while the bracket parts are locked together, means for holding the lamp post against rotation, a lamp carrying arm swiveled on the lamp post, means for holding said arm against rotation, and a mirror jointedly supported by the lamp carrying arm. 60

4. A lamp bracket comprising two parts hinged together, each part provided with half of a clamping neck for affixing to a support, a lamp post removably and rotatably mounted in one bracket part, means 70 for locking the bracket parts together, and said locking means including a member engaging with and rotatably securing the lamp against removal while the bracket parts are locked together. 75

5. A lamp bracket comprising two parts hinged together, each part provided with half of a clamping neck for affixing to a support, a lamp post provided with a peripheral groove and removably mounted in 80 one bracket part, means for locking the bracket parts together, and a bar reciprocable by the locking means and engaging with the peripheral groove in the lamp post. 85

6. A lamp bracket comprising two parts hinged together, each part provided with half of a clamping neck for affixing to a support, a lamp post removably mounted in one bracket part, means for locking the 90 bracket parts together, means operated by said locking means preventing the removal of the lamp post while the bracket parts are locked together, a spool journaled in the bracket, and an electric cord wound on the 95 spool, connected with the lamp socket carried by the lamp post.

WILLIAM W. SABIN.
